WINDOW FRAME

Application filed June 25, 1928. Serial No. 288,245.

Window frames as ordinarily made have no provision for drainage of moisture which accumulates around the casing and the blind stop during a rain, snow or sleet storm. This moisture, prevented from proper drainage through the structure of the frame, produces rot of the wood and frequently runs down on the inside of the casing and the frame into the walls of the building, resulting in loosening of the interior plaster and discoloration of the decorations.

The object therefore of our invention, is to provide a frame in which suitable provision is made for drainage without adding materially to the cost of manufacture.

Other objects of the invention will appear from the following detailed description:

The invention consists generally of various constructions and combinations, all as hereinafter described, and particularly pointed out in the claims.

In the accompanying drawings forming part of this specification,

Figure 1 is a front elevation of a window frame and casing embodying our invention;

Figure 2 is a sectional view on the line 2—2 of Figure 1;

Figure 3 is a detail sectional view showing a modification of the beveled lower face of the head casing;

Figure 4 is a perspective of the form of head casing shown in Figure 3;

Figure 5 is an end view of the head casing shown in Figure 4;

Figure 6 is an end view of the casing illustrated in Figures 1 and 2;

Figure 7 is a perspective view in section showing one means for draining the space on the inner side of the blind stop;

Figure 8 is a perspective view showing a modified construction of the drainage feature of the blind stop;

Figure 9 is a detail view showing another modification of the drainage feature of Figure 7;

Figure 10 illustrates another modification in the drainage feature of the blind stop; and Figure 11 is a perspective of the blind stop and drainage feature shown in Figure 10.

In the drawing, 2 represents the window sill; 3 are the side jambs having their lower portions secured to the sill in any suitable way; 4 is a head of the frame parallel substantially with the sill, and 5 and 6 are the side and top or head parting beads, all of well known construction in window frames. 7 represents the blind stop arranged on each side of the frame, and 8 is the corresponding stop at the head of the frame, forming a continuation of the side stop 7. 9 represents the side casings, between which, and the jambs 3 the blind stops 7 are arranged; 10 is the head casing. Usually the upper edge of this head casing is flat and level and provided with a water drip 11 which overhangs the front of the casing. We have found that in a driving rain or sleet storm, moisture will work in under this drip and often get in behind the casing and cause a rotting of the wood and sometimes work through the frame into the house. To avoid this, we provide an outwardly and downwardly inclined bevel 12 on the upper edge of the head casing so that if any moisture works in between the casing and the water drip, it will naturally flow outwardly and downwardly instead of into the space in the rear of the casing.

A further advantage derived from this construction lies in the fact that the water drip may be made of 1 inch lumber and still have all the appearance of the usual water drip made of one and one fourth inch lumber. With the accumulation of ice and snow on and around the water drip, moisture by capillary attraction will work in between the casing and the drip, but with this downward and outward bevel of the casing such moisture will flow back out of the joint and be discharged on the outer side of the casing. The

lower edge of the head casing also has a beveled or inclined face 13 and the upper ends of the side casing 9 have corresponding surfaces 14 to fit the lower edge of the head casing and form a close joint at this point with the meeting faces of the joint outwardly and downwardly inclined so that when moisture works in between the head and side casings, it will naturally flow by gravity outwardly and downwardly instead of into the space in the rear of the casing and into the window frame. This manner of forming the abutting faces of the head and side casings will not add to the cost of construction and will aid materially in preventing driving rain, sleet or snow from working into the joint and entering the window frame in the rear of the casing.

In Figures 3 and 4 we have shown a modification in the bevel on the lower edge of the head casing which consists in providing end bevels 13^a with a straight area 13^b between them, the areas 13^b receiving the upper ends of the side casing and forming a close joint therewith with the meeting faces of the joint outwardly and downwardly inclined. The intermediate part 13^b will be the portion of the head casing at the top of the window. With this construction it would be unnecessary to bevel the upper rail of the screen, as the flat face usually provided on the upper face of this rail would fit snugly against the corresponding face of the head casing.

In case the head casing is formed as shown in Figure 2 with the bevel extending the full length, then it will be necessary to bevel the upper rail of the screen to fit this surface, and in that case to hold the screen in place it will only be necessary to provide a hook and eye at the bottom, as the head of the screen will be held by the incline of the beveled meeting faces. Either of these constructions may be employed as the manufacturer may prefer.

The bevel on the lower edge of the head casing permits the use of one inch screen stock with a casing of an inch and a quarter stock. No hooks or hardware of any kind are needed at the head of the screen as it will be held in place by the bevel of the casing, the meeting beveled faces of the screen rail and casing holding the screen in position and making it unnecessary to have them of the same thickness. This will be convenient in placing and removing the screen and save some expense in manufacturing, by permitting use of smaller stock for the screen and eliminating the usual fastening means.

Turning now to another portion of the frame, Figure 7, the blind stop 7 is shown provided with its lower end cut away at 15, thus providing a water way for the moisture that may accumulate between the vertical blind stop and the parting bead 5. Generally this blind stop has its inner face extended down to the surface of the sill, forming a

wall that serves as a dam to hold snow or rain that may enter the space between the blind stop and bead, and allow it to work in between the sill and the jamb and cause rotting of the wood in time and in some cases accumulate sufficiently to enter the building walls around the frame.

In Figure 8 we have shown a modification which consists in beveling or cutting away the inner corner of the blind stop at 16, this having substantially the same effect as the bevel at 15, as shown in Figure 2. This construction is shown extending practically the exposed depth of the blind stop, or from the inner face of the stop to a point adjacent the corresponding face of the jamb. This cutting away of the corner will allow any moisture that accumulates between the blind stop and the bead to flow outwardly and downwardly over the sill and thus be expelled from the window frame.

In Figure 9 a modification is shown which consists in slotting or grooving the lower end of the blind stop at 17, thus providing a gap or passage through which the water may conveniently flow past the stop and out over the sill.

In Figure 10 we have shown a transverse recess 18 formed at the lower end of the blind stop, thus providing a gap between the stop and the face of the sill, and through this gap the moisture normally held back by the blind stop, will be discharged from the sill as fast as it falls thereon. This applies not only to rain water, but when ice and snow fall upon the sill and accumulates between the blind stop and the bead, the stop as usually formed prevents the melting ice and snow from being discharged. With our improvement, however, it will be practically impossible for moisture to be dammed up by the vertical blind stops and prevented from a rapid discharge from the frame.

We claim as our invention:

1. A window frame having side casings provided with outwardly and downwardly inclined upper faces, and a head casing having an under face formed to fit the corresponding faces of said side casings, for the purpose specified.

2. A window frame comprising side casings having their upper ends provided with outwardly and downwardly inclined faces, a head casing provided on its lower edge with a bevel formed to fit the corresponding faces of said side casings the middle portion of the lower edge of said casing having a beveled face to contact with the corresponding face of a screen rail, for the purpose specified.

3. A window frame and blind stops therefor, the lower ends of said stops abutting the sill being formed for the discharge of moisture accumulating between the blind stop and the adjacent parting bead.

4. A window frame having blind stops, the lower ends of which abut the surface of the sill, and said lower ends having beveled or cut away portions to prevent the accumulation of moisture between said stops and the parting beads.

In witness whereof, we have hereunto set our hands this 20th day of June, 1928.

FRED C. ANDERSEN.
